UNITED STATES PATENT OFFICE

2,664,628

POLE PRUNER HEAD

Thomas M. Porter, Brookline, Mass., assignor to
 H. K. Porter, Inc., Somerville, Mass., a corpora-
 tion of Massachusetts

Application November 16, 1951, Serial No. 256,736

2 Claims. (Cl. 30—249)

1

This invention relates to pole pruners of the type having a hook member, in the general form of an inverted J, across the throat of which sweeps a cutting blade, and the object is to provide improvements relating to the control of the blade whereby an efficient structure not likely to be fouled by twigs or the like is provided and one which may be economically produced.

My invention will be well understood by reference to the following description of the illustrative embodiment thereof shown by way of example in the accompanying drawings, wherein:

Fig. 1 is a fragmentary side elevation of a pole pruner illustrative of the invention;

Fig. 2 is a similar view showing the jaws closed; and

Fig. 3 is a section on line 3—3 of Fig. 1.

The pruner illustrated in the drawings comprises a J-shaped member which, as shown, is formed from two spaced identical elements 10—l and 10—r secured together at their distal ends and at the lower ends of the shank of the J. A cutting blade 12 is mounted on pivot 14 adjacent the upper end of the stem of the J and has an edge portion to sweep across the throat of the J to effect a cut in cooperation with the work-engaging portion. The parts 10—l and 10—r may be secured to the pole 15 by means of side plates 18—l and 18—r. What has been described in this paragraph is not in itself new.

The blade 12 has a rearward extension to provide a lever arm of suitable length to which rope 20 may be attached to operate the pruner. Herein this extension is formed by a straight, bar-like piece 22 riveted to the side of the blade. Economy in the use of the high-grade steel from which, for efficiency, the blade must be formed, is thus effected and another function is provided for as will hereinafter appear.

The blade is closed to the position of Fig. 2 by pulling on the rope 20, and some spring means is required to return the parts to the opening position. Springs as hitherto arranged on tools of this type cause trouble. In general they provide another obstruction at the head of the pruner, difficult to manipulate in tight places between the branches. Twigs are likely to get between the springs and other parts of the pruner head and interfere with its operation. The spring itself may be caught and found difficult to free, and may even be damaged.

I ameliorate these conditions by utilizing a cylindrically coiled spring 24 of the extension type, which is positioned so that its coils closely encircle the lever arm 22 which arm extends

2

through the spring substantially coaxially therewith. The ends of the spring are anchored respectively at 26 to the outer end of the lever arm and at 28 to the J-shaped member at a point suitably offset from the pivot 14. The latter anchorage is effected by a relatively long straight extension 30 of the wire of the spring which extension may lie close along the side of arm 22 and the back of the blade 12.

It will be apparent that the spring adds very little bulk to the necessary bulk of the blade lever itself and presents no parts widely spaced therefrom into which twigs or the like may enter. At the same time the spring is guarded and supported against damage by the member 22 over which it is telescoped.

The inner or lower end of the arm 22 projecting from the side of the blade 12 is in the plane of the J-shaped member 10—l on that side and it may thus be so arranged that it makes contact with the back of this member 10—l when the parts are closed when the blade has completed its sweep across the throat of the member as illustrated in Fig. 2. The hooked portion of the spring where anchored at 28 bridges the two side plates 18—l and 18—r and forms a stop presented to the side of the blade 12 when the parts are in the open position of Fig. 1.

I am aware that the invention may be embodied in other specific forms without departing from the spirit or essential attributes thereof, and I therefore desire the present embodiment to be considered in all respects as illustrative and not restrictive, as is in fact clear in several matters from the description itself. Reference is to be had to the appended claims to indicate those principles of the invention exemplified by the particular embodiment described and which I desire to secure by Letters Patent.

I claim:

1. A cutter head for pole pruners comprising a member of general inverted J form the curve of the J providing a work-engaging portion, a flat blade pivoted adjacent the upper end of the stem of the J and having an edged portion to sweep across the throat of the J to effect a cut in cooperation with said work-engaging portion, a straight bar-like lever arm rigidly associated with the blade and extending rearwardly therefrom and means for normally moving the blade to open position comprising a cylindrically coiled extension spring, the coils of which closely encircle the lever arm which arm extends through the spring substantially coaxially therewith, the ends of the spring being anchored respectively to

the outer end of the lever arm and to the upper portion of the J-shaped member at a point remote from the pivot.

2. A cutter head as defined in claim 1 wherein the lever arm is a separate member rigidly secured to one side of the blade and has an inner end upstanding from the side of the blade to provide a shoulder which contacts the back of the J-shaped member when the blade has completed its sweep across the throat of the member. 10
